VANITY BOX

Walter A. Goertz, Newark, N. J., assignor to
 August Goertz & Co., Inc., a corporation of
 New Jersey

Application March 16, 1933, Serial No. 661,037

6 Claims. (Cl. 132—83)

This invention relates, generally, to vanity boxes or compacts for carrying cosmetic materials; and the invention has reference, more particularly, to improvements in vanity boxes or compacts carrying loose powder or the like.

Vanity boxes for carrying loose powder, as heretofore generally constructed, have been somewhat objectionable in use owing to the tendency of the powder to escape or sift out around the edges of the covers of the powder compartments when these covers are closed; such escaping powder not only covering objects within the vanity box, but also escaping from the box, especially when the same is opened, to fall upon objects, thereby disfiguring the same in addition to the wasting of the powder.

The principal object of the present invention is to provide a vanity box having a novel construction of powder compartment, the said compartment being provided with means for sealing the joint between the compartment cover and the body of the compartment, thereby preventing the escape or sifting of loose powder outwardly therefrom.

Another object of the present invention lies in the provision of a vanity box having a novel construction of powder compartment of the above character, which powder compartment, in its preferred form, is provided with a false bottom serving to hold a felt disc or washer so that the peripheral edges thereof are adapted to engage the lower peripheral edge portions of the compartment cover in abutting relation when the cover is in closed position, to thereby prevent the escape of powder from the closed powder compartment.

Other objects of this invention, not at this time more particularly enumerated, will be clearly understood from the following detailed description of the same.

The invention is clearly illustrated in the accompanying drawing, in which:

Fig. 1 is a plan view of a vanity box embodying the improvements of the present invention, the body sections thereof being shown in open relation.

Fig. 2 is an enlarged part sectional view taken substantially along line 2—2 of Fig. 1, looking in the direction of the arrows.

Fig. 3 is a view similar to Fig. 1 but illustrates the powder compartment cover in open position.

Fig. 4 is an enlarged sectional view taken substantially along line 4—4 of Fig. 3, looking in the direction of the arrows.

Fig. 5 is a perspective view illustrating the

manner of assembling the several parts of the powder compartment.

Similar characters of reference are employed in all of the above described views to indicate corresponding parts.

Referring now to said drawing, the reference character 6 indicates a lower body section of the vanity box and 7 an upper body section thereof. Said body sections are respectively provided along their meeting rear edges with hinge knuckles 8, which interfit one with another to receive a hinge pin 9, whereby said sections are hingedly connected together so as to close one upon another. The periphery of the upper section 7 is provided, at the point thereof opposite its hinge connection with the lower body section, with a hinge lip 10 which is adapted to cooperate with a catch 11 provided at a corresponding point on the periphery of the lower body section 6. The hinge lip 10 and the catch 11 serve to interlock the sections 6 and 7 in closed relation.

A powder receptacle 12 is contained within the lower body section 6, the bottom 13 of this powder receptacle resting upon the inner wall surface of the lower body section. The powder receptacle 12 is illustrated as of cylindrical shape although this receptacle may have any other desired shape and has an upper outwardly extending transverse flange 14 of a shape conforming to the interior of the lower body section 6. The peripheral edge portion of the flange 14 is formed with a bead 15 terminating in a depending apron 16 that conforms closely to the upper inner side wall surface of the body section 6 and is retained within this body section as by friction or by the use of any suitable securing means.

The body section 6 and the cover section 7 are illustrated as of octagonal shape in plan but it is to be understood that these sections may have any desired shape, such as round or square. The bead 15 by extending 95 around the peripheral edge portion of the flange 14 and fitting snugly against the upper edge portion of the body section 6 produces a pleasing and attractive appearance.

Flange 14 is formed with an annular depression or recess 17 adjoining the interior of the powder receptacle 12 for receiving the conforming annular flange 18 of a powder compartment cover 19. The powder compartment cover 19 has the form of a shallow pan or receptacle providing an interior powder puff compartment 20 for receiving a powder puff 21. The flange 18 of cover 19 is provided near the point of connection of the upper and lower body sections with a hinge knuckle 22 that is engaged by a hinge pin 23 110

carried by the flange 14 of the powder receptacle 12.

A spring catch 24 is attached to the lower surface of flange 14 at a point diametrically opposite the hinge knuckle 22 and extends upwardly through an opening provided in this flange 14. Spring catch 24 has a catch projection 26 for engaging the upper surface of flange 18 to thereby hold the cover 19 in closed position. Spring catch 24 is provided with a releasing knob 25, which, when pressed radially outwardly with respect to the cover 19, serves to release this cover from projection 26, permitting the turning of this cover 19 about its hinged connection 22-23 to open position.

Contained within the powder receptacle 12, in overlying relation to the bottom 13 thereof, is a disc or washer of felt 27 which has an annular upturned peripheral edge portion or flange 28 that extends upwardly adjoining the inner surfaces of the side walls of the receptacle 12, the upper edges of the flange 28 being positioned to engage the peripheral edge portion of the cover 19 in abutting relation when this cover is in closed position.

Receptacle 12 has a false bottom 29 overlying felt disc or washer 27. False bottom 29 is in the form of a metallic disc having its peripheral edge portion rounded and upturned somewhat at 30. The center of the false bottom 29 is secured as by a rivet 31 to the bottom 13 of the powder receptacle 12. Rivet 31 extends through an aperture provided in the central portion of the felt washer 27 and serves to press the false bottom 29 downwardly upon this felt washer somewhat to thereby grip and positively retain this felt disc in desired position with its peripheral flange 28 projecting uniformly upwardly beyond the rounded peripheral edge portion 30 of the false bottom 29. The false bottom 29 thus serves to hold the upturned peripheral edge portion 28 of the felt disc in proper position for engaging the under-surface of the cover 19 all around the periphery thereof, to thereby prevent the escape of powder from within the powder receptacle 12 when the cover 19 is closed.

Above the false bottom 29 and under the cover 19, i. e. when this cover is in closed position, there is provided a powder compartment for receiving loose powder 32. Since the powder compartment is completely encircled by the upturned peripheral flange 28 of the felt, which felt flange is positioned to abut the peripheral edge portion of the cover 19 when this cover is in closed position, the felt flange 18 serves to seal the joint between the cover 19 and the powder receptacle 12, thereby preventing the escape or sifting of powder from the powder compartment so long as the powder compartment is closed. When it is desired to remove powder from the powder compartment, it is merely necessary to press upon knob 25 of spring catch 24, thereby permitting the moving of cover 19 to open position, whereupon the powder puff 21 may be employed for removing the powder in the usual way.

As many changes could be made in the above construction and many apparently widely different embodiments of this invention could be made without departing from the scope thereof, as defined by the following claims, it is intended that all matter contained in the above description or shown in the accompanying drawing shall be interpreted as illustrative and not in a limiting sense.

What is claimed is:

1. A vanity box comprising, a lower body section and a cooperating upper body section, said lower body section having a powder compartment provided therewithin, a cover for said powder compartment, a felt washer overlying the bottom of said powder compartment and extending upwardly at the sides of said compartment, the upper edges of said felt washer being positioned to abut the lower peripheral edge portion of said cover, to thereby seal the joint between said powder compartment and said cover. 80

2. A vanity box comprising, a lower body section and a cooperating upper body section, said lower body section having a powder compartment therewithin, a cover for said powder compartment, a felt washer overlying the bottom of said powder compartment and extending upwardly at the sides thereof, a retaining member for holding said felt washer in fixed position within said powder compartment, the upper peripheral edge portion of said felt washer being positioned to abut the lower surface of said cover along the line of juncture of this cover with the walls of the powder compartment, to thereby seal the joint 100 between said powder compartment and said cover. 90

3. A vanity box comprising, a lower body section and a cooperating upper body section, said lower body section having a powder compartment therewithin, a cover for said powder compartment, a felt washer overlying the bottom of said powder compartment, a false bottom provided within said compartment in overlying relation to said felt washer, fastening means for holding said false bottom in binding relation upon said felt washer to retain the latter in fixed position, said felt washer having an upturned peripheral edge portion extending upwardly between the peripheral edge of said false bottom and the side walls of said compartment, the upper edge of the peripheral edge portion of said felt washer being arranged to abut said cover all along the line of juncture of the same with the side walls of said powder compartment when the cover is in closed position, to thereby seal the joint between said powder compartment and said cover and prevent the escape of powder therefrom. 115

4. A vanity box comprising, a lower body section and a cooperating upper body section, a powder receptacle provided within said lower body section, a cover for said powder receptacle, a felt washer overlying the bottom of said powder receptacle, said powder receptacle having a false bottom overlying said felt washer, the peripheral edge of said false bottom terminating short of the side walls of said powder receptacle so as to enable a portion of said felt washer to extend upwardly between said false bottom and the side walls of the powder receptacle, the upper edge portion of said washer being positioned to abut the lower surface of said cover along the line of juncture of this cover with the side walls of said powder receptacle, to thereby seal the joint between said powder receptacle and its cover. 12

5. A vanity box comprising, a lower body section and a cooperating upper body section, a powder receptacle fixed within said lower body section, said powder receptacle having a bottom and side walls and being open at its top, a cover for said powder receptacle, a felt washer overlying the bottom of said powder receptacle, said powder receptacle having a false bottom overlying said felt washer, riveting means extending between 13

the bottom of said powder receptacle and the false bottom thereof for binding said false bottom against said felt washer, to thereby retain the latter in fixed position within said powder receptacle, the peripheral edge of said false bottom being curved upwardly and terminating short of the side walls of said powder receptacle so as to enable a portion of said felt washer to extend upwardly between said false bottom and the side walls of the powder receptacle, the upper edge portion of said felt washer being positioned to abut the lower surface of said cover along the line of juncture of this cover with the side walls of said powder receptacle, to thereby seal the joint between said powder receptacle and its cover.

6. A vanity box comprising, a lower body section and an upper body section hinged together, a powder receptacle contained within said lower body section, said powder receptacle having a bottom and side walls and a transverse flange projecting outwardly from the upper edges of said side walls, said transverse flange having its peripheral edge portion attached to the inner

walls of said body section, a cover for said powder receptacle, said cover being hingedly connected to said transverse flange, a felt washer overlying the bottom of said powder receptacle, said powder receptacle having a false bottom 80 overlying said felt washer, riveting means extending between the bottom of said powder receptacle and the false bottom thereof for binding said false bottom against said felt washer to thereby retain the latter in fixed position within 85 said powder receptacle, the peripheral edge of said false bottom terminating short of the side walls of said powder receptacle so as to enable an annular portion of said felt washer to extend upwardly between said false bottom and the side 90 walls of the powder receptacle, the upper peripheral edge portion of said washer being positioned to abut the lower surface of said cover along the line of juncture of this cover with the side walls of said powder receptacle, to thereby seal the 95 joint between said powder receptacle and its cover.
